United States Patent Office.

JOHN ROGERS, OF NEW YORK, N. Y.

Design No. 3,169, dated August 25, 1868.

DESIGN FOR GROUP OF STATUARY.

The Schedule referred to in these Letters Patent and making part of the same.

TO ALL WHOM IT MAY CONCERN:

Be it known that I, JOHN ROGERS, of the city, county, and State of New York, have invented or produced a new and original Design for a Group of Statuary; and I do hereby declare that the following is a full and exact description of the same.

It is called "Courtship in Sleepy-Hollow," and is designed from Washington Irving's story of "The Legend of Sleepy-Hollow."

It represents Ichabod Crane and Katrina Van Tassel seated on a Dutch settle. Katrina's left hand rests on a kitten, which is in her lap, while she is receiving in her right hand a bouquet, which Ichabod is urging her to accept, all of which is fully shown in the accompanying drawings.

Having thus described my invention, what I claim, and desire to secure by Letters Patent, is—

The design for a group of statuary, as herein shown and described.

JOHN ROGERS.
